UNITED STATES PATENT OFFICE.

GEORGE A. MEELL, OF PHILADELPHIA, PENNSYLVANIA, ASSIGNOR TO THE BAILEY,
BANKS & BIDDLE COMPANY, OF PHILADELPHIA, PENNSYLVANIA, A CORPORATION
OF PENNSYLVANIA.

DESIGN FOR A CLASS RING.

Application filed June 11, 1923. Serial No. 6,472. Term of patent 3½ years.

To all whom it may concern:

Be it known that I, GEORGE A. MEELL, a citizen of the United States, residing in the city and county of Philadelphia, State of Pennsylvania, have invented a new, original, and ornamental Design for Class Rings, of which the following is a specification, reference being had to the accompanying drawing, forming part thereof.

The figure is a top view of a class ring showing my new design.

I claim:—

The ornamental design for a class ring, as shown.

GEORGE A. MEELL.
